UNITED STATES PATENT OFFICE.

SILAS E. JERALDS AND EDWIN R. LAWTON, OF CHESHIRE, CONNECTICUT.

HANDLE FOR CUTLERY.

SPECIFICATION forming part of Letters Patent No. 336,116, dated February 16, 1886.

Application filed March 8, 1884. Serial No. 123,487. (No model.)

To all whom it may concern:

Be it known that we, SILAS E. JERALDS and EDWIN R. LAWTON, both of Cheshire, in the county of New Haven and State of Connecticut, have invented certain new and useful Improvements in Handles for Cutlery and the Like; and we do hereby declare that the following is a full, clear, and exact description thereof, whereby a person skilled in the art can make and use the same, reference being had to the accompanying drawings, and to the letters of reference marked thereon.

Like letters in the figures indicate the same parts.

Figure 1 is a plan view of a blank as cut from sheet metal in the first step for the production of our invention. Fig. 2 is a side view of the sheet-blank when folded to tubular form, and also an end view showing the section-outline. Fig. 3 is an edge view of this tubular form, showing the seam where the edges of the sheet-blank are united. Fig. 4 is a side view of the handle formed by bending down the projections at the butt-end of the blank. Fig. 5 is an edge view of the handle, showing the seamless edge of the same. Fig. 6 is a view in cross-section of the sheet-blank on plane denoted by line xx of Fig. 1. Fig. 7 is a view in cross-section of the handle on plane denoted by line yy of Fig. 4. Fig. 8 is a view of the butt-end of the handle, showing the seam where the projections join when the butt is formed. Fig. 9 is a view of a tubular blank, showing side and end views. Fig. 10 is a view of a tubular blank as tapered and having the butt-end cut to form for closing, also an end view showing the sectional outline. Fig. 11 is a view of the handle formed by closing the ends of the tapered blank by bending down and uniting the projections.

In the subdivisions of trades and the mechanic arts resulting from the extensive use of labor-saving machinery many articles are produced in parts in widely-separated factories, and are united or assembled into the desired resulting form or machine at still another shop. A given article bought from one specialist is subjected to further operations by a second, and perhaps a third, manufacturer before reaching the final stages of its incorporation in one or the other of the devices to the completion of which it may be essential. To this

general class belongs the article that forms the subject-matter of our present application, and the particular class to which our improvement relates is handles for table-cutlery and the like. It is obviously adapted to other uses; but it suffices to describe the article as made for this specific use.

In the accompanying drawings, the letter a denotes a blank struck from sheet metal of the desired thickness by any well-known method. The edges of the blank illustrated are tapered, and the wider end formed with circular projections a' a'' , whose bounding surfaces unite at the center line of the blank. This blank is next bent into a tubular form of circular or oval outline of cross-section in such manner that the edges may be united by brazing or soldering. This bending may be done upon a mandrel—that is, withdrawn from the larger end of the tubular blank b after forming it. After uniting the edges a^3 a^4 the projections are bent inward, as by means of dies, and the butt-end closed by uniting the edges by brazing or soldering, and the handle, so far as we are concerned, is completed in form for sale to other manufacturers.

In Figs. 9, 10, and 11 is illustrated the form of the blank and handle as made by an alternate method, and in this we first cut from a metallic tube a blank, d , of desired length. Then form it to a taper and an oval outline of cross-section, as by use of a tapered and oval mandrel. The larger end is cut to form the projections d' d'' , which are then turned inward, joined, and soldered or brazed, forming the handle e , as seen in Fig. 11.

We may make this improved handle in any form as to cross-section, as circular, oval, or oblong, with rounded edges, and with parallel or tapered sides for the whole or part of its length.

We are aware that a hollow handle for cutlery has been formed from a plate-metal blank by folding it to shape and closing one end by folding over it a rectangular projection on the blank, as shown in the patent to C. Ulmer, dated February 4, 1862, No. 34,337, and a handle formed from a plate-metal blank with an end flap we do not broadly claim.

Our device possesses an advantage over prior blanks for handles in that the peculiar construction of the circular projections or ears

and their relative position on the blank when it is formed or rolled up to the tubular shape, as shown in Figs. 2, 3, and 10, enable the end of the handle to be closed between dies that bring the edges of the ears together and form the rounded and oval end without the aid of a mandrel. This is of great advantage in making handles that taper on all sides toward the tang end, as a mandrel cannot be used in such in this final operation of closing the end. The curved shape of the edges causes them to meet in such manner as to fill out and round out the handle end into the mortise or socket in the finishing-dies.

15 The method or process of making the article forming the subject-matter of the present application has been patented to us under date of March 11, 1884, No. 295,016, and therefore no specific claim to the method is made herein.

We claim as our invention—

As an improved article of manufacture, a handle for cutlery and like articles, consisting of a hollow shell with one end open, and the other closed and rounded, composed of a single piece of metal with its edges united in one seam running from the open end of the handle along one side, across the center of the rounded end, and terminating at the point where the rounded end meets the opposite side, all substantially as described.

SILAS E. JERALDS.
EDWIN R. LAWTON.
